IMAGE TRANSFER MECHANISM FOR ELECTROSTATICALLY ADHERING IMAGES

Clyde R. Mayo and William G. Lewis, Rochester,
N. Y., assignors to The Haloid Company, Rochester, N. Y., a corporation of New York

Application November 23, 1951, Serial No. 257,872

2 Claims. (Cl. 95—1.9)

1

This invention relates to paper or sheet feeding, placing or advancing mechanisms, and to the combination of such mechanisms with plates or surfaces carrying pigment or powder images to be transferred and electrostatic transfer elements to effect transfer of such images to paper or other sheet material.

An important application of the mechanisms herein disclosed resides in their use in equipment for electrophotography, now commonly called xerography, in which an electrostatic latent image is formed on a sensitized photoconductive surface, the image is developed with a finely-divided material, such as a pigmented powder, and then the powder or other material is transferred to paper or other sheet material where it can then be affixed, if desired, to form a permanent image.

One transfer mechanism used in xerography includes an ion source, such as a high voltage corona electrode. The "transfer sheet," i. e., a sheet of paper or other material, is placed on the photoconductive surface carrying the "image material," such as powder, pigment or other material, and the assembly is passed under the ion source, such as a grid of corona wires, which is spaced a short distance above the transfer sheet and is held at a high potential with respect to the support for the photoconductive surface. The transfer sheet is thus charged by the ion source to a potential sufficient to attract the image material and cause it to adhere electrostatically to the transfer sheet. The sheet is then stripped off the plate and carries the image with it.

During transfer by this method the electrostatic charge applied to the transfer sheet produces a fairly strong adhesion between the sheet and the image-bearing surface. In fact, once the leading edge of the sheet is "pinned" to the surface by the charge, the attractive force is adequate to pull the sheet along with the surface even if a substantial amount of drag or back-pull is present in the feeding device for the sheets. It is of importance, however, that the sheet material be accurately and smoothly placed against the image surface so that there will be no subsequent shifting or slippage to produce smudging. If bulges or wrinkles are present when the sheet is first placed in position, such slippage and smudging may occur as the sheet is flattened against the surface. More serious than this is the situation in which a transfer sheet contains bulges and wrinkles which cannot be flattened down by the electrostatic forces. This results in a deletion of part of the image since sub-

2

stantially direct contact is necessary to effect good transfer of the powder or other material.

Rollers pressed against the sheet during transfer have been successfully used in some applications. However, they do not completely eliminate the smudging and deletion problem. Thus, as the roller passes over the transfer sheet, it may sometimes cause a shifting of the sheet or some areas of it as they are flattened out. Moreover, since the ion source ordinarily does not charge the sheet until it has passed out from under the roller there is an opportunity for bulges and wrinkles to re-form after the sheet is released by the roller and before it is pinned down by the electrostatic charge. Another disadvantage of contact rollers resides in their tendency to pick up image material from the margins or from the image area when a transfer sheet is accidentally not fed into position. Such material will then be offset onto the back of a subsequent sheet. Very precise control of roller pressure is also required with contact rollers, since light pressure may fail to iron out all the bulges and wrinkles and heavy pressure may produce compression and adhesion of the image material to the original surface and defeat electrostatic transfer to the overlying sheet, making cleaning of the plate difficult. Damage to the plate may also result.

The present invention contemplates novel sheet feeding mechanisms and combinations including such mechanisms in which the feeding mechanisms are spaced from an image surface from which an electrostatic transfer is to be made, and sheet material is fed against the surface in a curved condition, whereby wrinkles and bulges are eliminated prior to and during electrostatic transfer of an image material, and the problem of accurate matching of the sheet feeding to the image surface speed is reduced.

The preferred embodiment of the invention comprises mechanisms for feeding transfer sheets against surfaces carrying electrostatically deposited powder images preparatory to electrostatic transfer of such images to the sheets. Such surfaces may comprise electrophotographic or xerographic plate surfaces, xeroprinting plate surfaces and the like.

The invention comprises the features of construction, combination of elements, arrangement of parts, and methods of operation referred to above or which will be brought out and exemplified in the disclosure hereinafter set forth, including the illustrations in the drawing.

In the drawings:

Figure 1 is a vertical section showing a portion

of a xerographic processing unit embodying features of the present invention;

Figure 2 is a fragmentary section on the line 2-2 of Figure 1;

Figure 3 is a vertical section through another form of transfer device for transferring powder or pigment images from electrostatic image plates;

Figure 4 is a top view of the device of Figure 3 with parts broken away for illustration;

Figure 5 illustrates the invention applied to a cylindrical drum machine;

Figure 6 is a vertical section through a further modified form of the invention; and

Figure 7 illustrates preferred features of the invention.

While a preferred embodiment of the invention is described herein, it is contemplated that considerable variation may be made in the construction and arrangement of parts and in the method of operation without departing from the spirit of the invention. In the following description and in the claims, parts will be identified by specific names for convenience, but they are intended to be as generic in their application to similar parts as the art will permit.

Referring to Figures 1 and 2 of the drawings, the invention is illustrated in connection with a xerographic processing unit in which a xerographic plate 10 is mounted in a sloping position on a stationary base plate 11. The xerographic plate is arranged to be charged in the dark, then exposed to a light image projected onto its surface, then developed by cascading a developing powder composition over its surface to leave a powder image deposited upon the electrostatic latent image formed during the exposure. The mechanisms for performing the exposing and developing steps are not here illustrated since they form no part of the present invention.

The present invention contemplates mechanisms for effecting a transfer of the powder image formed on the plate 10 and such mechanisms are illustrated in the drawings wherein the moving carriage assembly 12 is arranged to travel up and down over the surface of the plate and to feed a sheet of transfer material, such as paper, against the plate for the purpose of making a transfer of the powder image.

The carriage 12 comprises a pair of parallel vertical side plates 13 rigidly spaced by frame members such as L-shaped members 14 and 15 to straddle the plate. A pair of stationary gear racks 16 are mounted in spaced parallel relation along the sloping edges of base plate 11 so that lower edges of side plates 13 extend down between the edge of the base plate and gear racks 16.

A pair of smooth tracks 17 are provided along the inner sides of gear racks 16 and spaced pairs of idling rollers 18 and 19 mounted on pintles in side plates 13 are arranged to ride on the top and bottom faces of tracks 17 to guide the carriage assembly and keep it accurately positioned with respect to the face of the xerographic plate.

Carriage 12 is moved up and down over the plate by a drive mechanism comprising reversible electric motor 20 and a drive chain 21, which drives a pair of endless chains 22, running on spaced sprockets 23 on shafts 24 which extend across the machine underneath the plane of the plate and beyond the upper and lower ends of the plate. The chains 22 are bolted to the lower edges of side plates 13 of the carriage so that travel of the chains 22 raises or lowers carriage

12 along its tracks, depending upon whether chains 22 are rotated in a counterclockwise or a clockwise direction (as viewed in Figure 1). Motor 20 may be controlled by a manual switch, or an automatic cycling circuit, and travel-limiting switches may be provided at the top and bottom of the tracks to de-energize the motor when the carriage reaches the end of the track.

Carriage 12 carries a corona discharge electrode comprising a grid of fine wires 30 which are stretched across the plate 10 in a horizontal direction, the grid being parallel to the plate surface and spaced from it a short distance, such as $\frac{1}{2}$ ". Grid 30 is connected to a high voltage source 31 such as a transformer-rectifier system capable of supplying several thousand volts potential, for example, 7,000 volts, to the grid wires 30. The wires are supported at their ends on a pair of spaced insulating blocks 32 mounted under a flange of frame member 14. The grid 30 consists of three parallel corona emission wires uniformly spaced from the plate 10 and a fourth parallel corona wire 33 is also connected to the same high voltage source but is mounted slightly closer to the plate surface. A control grid of wires 34 which is formed of larger diameter wires, is supported from blocks 32 between grid 30 and the plate. Grid 34 does not however, extend in front of corona wire 33. Control grid 34 is connected to a lower voltage terminal 35 of the high voltage supply so that grid 34 is held at a potential between that of corona wires 30 and ground. Thus a potential of about 400 or 500 volts may be used on grid 34. This effects a measure of control over the potential of charge applied to the photoconductive insulating coating on xerographic plate 10 by corona wires 30. Thus when the potential of the coating reaches substantially the voltage of grid 34 the flow of charged ions to the plate substantially ceases.

A grounded conductive shield 36 is mounted behind the corona wires 30 and 33 in order to improve the characteristic of the corona discharge.

The corona discharge assembly just described may be used for charging xerographic plate 10 preparatory to exposure to a light image and the same corona may subsequently be used for effecting electrostatic transfer of the image to a sheet of transfer material. During charging of the plate the carriage is preferably advanced upward over the plate surface so that corona wire 33 precedes wires 30 and the control grid 34 over the plate.

Since corona wire 33 is not shielded by grid 34 its rate of charging the plate is rapid and it serves to charge the plate up to substantially the desired potential. The rate of travel of the carriage is sufficiently great so that there is no danger of overcharging from the single corona wire. Following wire 33 the shielded corona wires 30 add further charge to the plate surface under control of grid 34 so that a uniform and controlled potential is thus applied to the plate.

After exposure and development of the image, carriage 12 is again brought to the bottom of the plate 10 in preparation for transferring the powder image to a sheet of paper or other transfer material.

The transfer mechanism, embodying features of the present invention, comprises a pair of sheet feed rollers 37 and 38 for receiving and feeding a sheet of paper or other transfer material against the xerographic plate and the powder image carried by it and under the corona discharge assembly. The sheet feed rollers are

spaced from the plate surface and are arranged to feed the sheet against the plate at a substantial angle so that the sheet is bowed into a substantial curve just preceding its point of contact with the plate and just prior to its passage under the corona discharge assembly. The rollers are driven by gears cooperating with gear racks 16 at a surface speed at least equal to the rate of travel of the carriage and preferably slightly in excess of it so that the bow in the sheet being fed against the plate is increased slightly during carriage travel, all of which has the beneficial effect of pressing the transfer sheet more firmly against the plate as travel proceeds.

Feed roller 37 is in the form of a sleeve on a horizontal shaft 25 which runs in bearings 26 located in side plates 13 of the carriage at a position above the corona assembly. A spur gear 27 is keyed to each end of shaft 25. A pair of pinion gears 28 are supported on pintles 29 on the carriage in positions to mesh with gear racks 16 and with spur gears 27. As carriage 12 is driven up and down the tracks by motor 20, shaft 25 is rotated at a speed which is arranged to give a surface speed to roller 37 which is at least equal to, and preferably 0.5 to 5% greater than the speed of the carriage. This is accomplished by making the diameter of feed roller 37 equal to or slightly larger than the pitch diameter of spur gears 27.

Roller 38 is mounted parallel to roller 37 with its surface in contact with roller 37 so as to be driven by it. The tangent plane at the line of contact is substantially vertical so that it intersects the surface of plate 10 at an acute angle, and at a position just ahead of corona wire 33. Shield 36 is preferably bent downward and bevelled inward along its upper margin, as shown, to terminate at an edge just above the plate surface providing a small clearance, such as $\frac{1}{4}$ ", at substantially the line of intersection between the tangent plane and the plate surface. Rollers 37 and 38 are preferably surfaced with rubber layers 39 and 40 respectively, although in some cases other surfacing materials may be used or rubber may be applied to one of the rollers and the other may be provided with a knurled metal surface.

In the transfer operation, when a powder image has been produced on plate 10 and carriage 12 is at the lower end of its path of travel, the operator inserts the end of a sheet of paper down between rollers 37 and 38 and energizes motor 20 to start the travel of the carriage upward over the plate. As travel begins rollers 37 and 38 grip the leading edge of the sheet and feed it downward into contact with plate 10 at an acute angle with the plate surface. As travel continues, the leading edge of the sheet is fed under the turned-down flange of shield 36 and comes under the influence of the corona discharge from corona wire 33 and subsequently from corona wires 30. As soon as the transfer sheet passes into the corona discharge zone an electrostatic charge is deposited on the back of the sheet by the electric discharge from the corona wires and the sheet is attracted tightly against the surface of plate 10 by electrostatic attraction. This brings the section of the transfer sheet which is between rollers 37 and 38 and the surface of the plate into the form of a curve or channel which effectively smooths out wrinkles and bulges which may be present in the sheet material and brings the sheet against the plate surface smoothly and uniformly along 70

a line extending across the width of the plate just ahead of the corona assembly. At the same time, or immediately thereafter, the corona discharge deposits a charge on the sheet to pin it smoothly to the plate surface and also to effect a transfer of the powder image to the transfer sheet.

As the carriage 12 continues to advance upwardly, the entire transfer sheet is fed progressively against the plate and adhesion of the powder or other transfer material to the sheet is effected. The carriage is preferably arranged to continue its travel above the top edge of the plate for a sufficient distance to enable the top edge of the transfer sheet, which finally lies flat, on the plate surface, to be reached by the operator. It is then possible for the operator to grasp the upper edge of the sheet and peel the sheet from the plate with its attached powder image. The sheet may then be placed in an oven or fed through a suitable fusing device to affix the powder to the sheet by fusion and form a permanent fixed image. The plate may be subsequently cleaned of any residual powder by any suitable method and the cycle repeated to produce further copies by recharging, exposure, development and transfer.

Figures 3 and 4 illustrate a transfer apparatus suitable for making transfers from movable plates which can be fed through the machine along with paper or other transfer material. This transfer device comprises a frame 41 having a pair of vertical end plates 42 between which the operating parts are mounted. The frame 30 is mounted in a generally rectangular opening in a top panel 43 of a box-like base 73 in which are mounted a drive motor 44 and a high voltage corona power supply 45. Panel 43 forms a horizontal feed plate with its upper surface 35 substantially midway between the top and bottom edges of frame 41. It is surfaced with sheet metal plates 46 which run lengthwise of the surface. Guide strips 48 of L-shaped cross-section are mounted along the outer edges of plates 46 to guide an image plate through the transfer device as the operator slides it into the feed rollers and the rollers carry it through the transfer mechanism.

The operating parts mounted between plates 50 42 include a pair of input feed rollers 47 and 48, a paper feed chute 49, paper edge guides 149, paper feed roll 50, paper feed idling roller 51, corona discharge assembly 52, and output feed rollers 53 and 54. All the feed rollers preferably comprise rubber covered metal rolls. Upper output roller 54, as shown in Figure 4 (and likewise upper input roller 48) comprises a central shaft provided near its ends with a metal sleeve which is surfaced with the rubber covering, so that the roller engages only the edges of the top surface of an image plate fed through the machine and does not roll on the image-bearing central area of the plate or ride on the transfer sheet which is fed against the plate by the paper feed rollers. The remainder of the rollers are of uniform diameter and are rubber-surfaced throughout their working length.

Lower input and output feed rollers 47 and 53 run in bearings in end plates 42 and are positioned near the input and output edges, respectively, of the frame 41 and below the plane of the feed plates 46 with their surfaces substantially tangent with that plane, or slightly above the tangent position. It is thus possible to slide 60 an image plate along plates 46 smoothly onto

the input roller 47, and for output roller 53 to feed the plate out onto plates 46 at the output side of the frame, which is at the left in Figures 3 and 4.

A metal slide plate 55 is adjustably mounted between walls 42 by flanges 56 to provide a table portion having its upper surface substantially in the plane of the feed plates 46 to provide a sliding surface and electrical ground for image plates as they pass under the corona assembly 52 between the input and output rollers.

The frame 41 is itself mounted in the opening in the base box by mounting brackets 57 to which the end plates 42 are secured by height-adjusting screws 59 to permit accurate adjustment of the height of the entire mechanism with respect to top panel 43 of the base box.

Lower input roller 47 carries a sprocket 59 on one end of its shaft by which it is driven by geared-down motor 44 through chain 63. Roller 47 carries a spur gear 61 on the same end of its shaft outside plate 42 and roller 48 has a meshing gear 62 to drive it at the same speed as 47. A chain of gears 63, 64, and 65 are also driven by gear 61 and gear 65 drives a spur gear 66 on the end of the shaft of output roller 53 which is thereby driven at the same peripheral speed as roller 47. Roller 54 is driven by a gear 61 on its shaft, which meshes with gear 66. Paper feed roller 58 carries a gear 68 which meshes with gear 63. Gear 68 is slightly smaller in pitch diameter than gear 61 while roller 58 is the same size as roller 47, so that the paper feed roller advances at a slightly faster rate than the plate feed roller, such as 0.5 to 5% faster. Idling roller 51 is surface-driven by roller 58 and is held against it by plungers 85.

Upper input and output feed rollers 48 and 54 travel in bearings mounted in swinging arms 69 and 70, respectively, pivoted on end plates 42 to allow them to be raised away from the lower rollers to admit an image plate between the rolls. The upper rollers are normally held against the lower feed rollers by spring-pressed plungers 75 which press against swinging arms 69 and 70. Arms 69 are provided with upward extensions 71 having circular cam openings in the upper ends through which a control shaft 72 extends. Shaft 72 carries a handle 73 at one end and a pair of cam pins 74 which ride against the inside of the cam openings. When handle 73 is in one position, the cam pins allow plungers 75 to hold the input rollers in contact but when handle 73 is manually rotated the pins 74 will lift the upper roller 48 away from the lower roller by a distance sufficient to provide easy sliding clearance for the end of an image plate as it is inserted into the machine. The control arm can then lower the roller 48 onto the top surface of the plate where it is held by plungers 75.

An indexing stop arm 76 is supported on shaft 77 to be swung upward into the path of an image plate which has been slid between rollers 47 and 48. Arm 76 is adjustable by a screw and slot combination to enable the starting position of the leading edge of the image plate to be set. An arm 79 is fixed on one end of shaft 77 and its end is pivotally connected to one end of a link 80 which rides on an eccentric cam portion of shaft 77 so that when handle 73 is turned to raise roller 48 the stop arm is also raised into operative position.

Corona discharge assembly 52 comprises a grid of fine wires 81 strung on pins mounted in a pair of insulating blocks 82 secured to the

lower face of a horizontal metal plate 83 and connected to a high voltage D. C. terminal of power supply 45. A shield plate 84 extends down from plate 83 and is curved inward at a position near slide plate 55 to afford a sloping guide insuring that the transfer paper will pass under the corona grid without striking it.

In operation of the device of Figures 3 and 4 an image plate, such as a rectangular flat xerographic plate, carrying an image material to be transferred, such as an electrostatically adhering powder image, is laid on top panel 43 and handle 73 is turned to raise roller 48 and stop 76. The plate is then slid between rollers 47 and 48 until its front end engages stop 76 after which the handle is again turned to remove stop 76 and to drop roller 48 against the margins of the image plate outside the image area. A sheet of transfer material, such as paper or an offset duplicator mat of the desired size is laid in paper feed chute 49 with its leading end in the wedge-shaped spaced formed by feed rollers 53 and 51. The tangent plane of contact between paper feed rollers 53 and 51 intersects the path of the image plate at an acute angle, such as 45 degrees, and at a point just beneath the curved lower edge of corona shield 84.

The operator now closes a switch 86 to energize the power supply and motor 44 and the rollers thereupon will advance the image plate along the top of slide plate 55. At the same time the paper feed rollers advance the transfer sheet down into contact with the plate where it bends into a curved channel as it passes under shield 84 and into the corona discharge now being produced by grid 81. The sheet is attracted to the image plate by the electric charge, and due to the curve in the sheet, all wrinkles or bulges are removed prior to contact with the image plate and uniform contact with the plate results as the sheet enters the corona zone where it is then held flat by the electrostatic attraction. Due to the slightly higher speed of the transfer sheet the curve in the sheet moves back slowly as the sheet advances to form a double bow or S-shape as indicated by the dashed line 87. This tends to increase the pressure with which the sheet is fed against the plate and also insures that there will be no tension applied to the sheet and that it will not rub against shield 84. After the sheet and image plate have passed under the corona assembly in contact and they have issued from between rollers 53, 54 the machine is stopped by opening switch 86 manually or by a control lever actuated by the plate and the transfer sheet with adhering image is manually stripped off the image plate.

Figure 5 shows a drum copying machine embodying features of the invention and comprising a cylindrical drum 88 which is surfaced with a coating of photoconductive insulating material. The drum is rotated in a clockwise direction by a drive motor and means are provided within housing 89 for charging its surface, exposing it to a light image and developing the image with powder, as described for instance in Carlson Patent 2,357,809. The developing means may be similar to that shown in the Carlson patent or may comprise a hopper system such as is disclosed in the application of R. M. Schaffert, Serial No. 55,816, filed October 21, 1948, now U. S. Patent No. 2,576,047.

The mechanism for transferring the powder image to paper comprises a pair of rubber-covered feed rollers 90, 91 spaced slightly from the drum

and whose tangent plane of contact intersects the surface of the drum at an angle of approximately 45 degrees. Roller 90 is driven intermittently at the same surface speed, or a slightly higher speed than drum 88 by a drive gear 92 which meshes with a gear attached to the end of roller 90. Gear 92 is attached to a smaller gear 93 which meshes with a segment gear 93 on the shaft of drum 88. A paper feed plate 93 supports a stack of paper 94 to be fed between the rollers, one sheet at a time, by pusher arm 95 which is oscillated by lever 96 attached to cam following rod 97 which is oscillated by cam 98 on the shaft of drum 88. A sheet is brought between the rollers by the pusher arm and the rollers feed the sheet against the drum as a powder image on the drum passes the transfer station. As a sheet of paper is fed against the drum it passes above corona discharge assembly 92 and the paper is electrostatically charged and thereby held against the drum and the powder image transferred. Further advance of the drum brings the paper to a suitable stripper 99 which peels it from the drum and feeds it through a fusing oven or other fixing device 100 to fix the powder image on the sheet.

Figure 6 shows manual transfer arrangement comprising a base plate 101 over which a corona discharge assembly 102 is bridged. A paper feed chute 103 is also bridged across the plate. This comprises a feed plate 104 supported at an angle of 45 degrees to the top of base plate 101, and a shorter upper plate 105 spaced above plate 104 to provide a paper feed slot 106 between them along the lower portion of plate 104. For making a transfer the operator energizes the corona discharge grid and slides an image plate 107 under chute 103 and under corona shield 108 into the zone of the corona discharge. At the same time he manually feeds a sheet of paper 109 down feed plate 104 and through the feed slot 106 until it strikes the top of plate 107. The motions are manually co-ordinated to locate the end of the paper in the desired position on plate 107 and then the assembly is pushed on through the corona zone. The sheet 109 is pushed with the hand just enough to maintain the desired curvature at the point where the paper enters the corona zone.

Figure 7, which refers to Figure 6, but applies to the other forms as well, shows the preferred relationship of paper 109 and image plate 107 during transfer, although these conditions can be departed from to some extent without serious loss of image transfer. The paper approaches the plate at an acute angle, of which 45 degrees is a satisfactory example, although the angle may vary from about 5 degrees to 90 degrees depending on the nature of the transfer material and other conditions. For most applications it is preferred to keep the angle between 5 and 85 degrees.

Near the plate the transfer sheet is bent into a curve or channel 109 which merges with the leading portion of the sheet which lies flat on the image plate and is held firmly in position by the electrostatic charge applied to it by the ion source, such as the corona wire grid 103. In the preferred form, the channel 109 merges with the plate 107 at margin of the corona zone. This margin can be rather sharply determined by shield plate 108 so the initial line of merging may be closely determined. However, if a shield is not used, or the lower edge of the shield is spaced quite far from the plate there may be

a zone of decreasing corona intensity and generally speaking contact anywhere in this zone, or even slightly in advance of it, will be satisfactory. As soon as the leading edge of the sheet is pinned down by the corona the electrostatic forces will tend to draw the sheet down against the plate and shift the line of merging to the left as viewed in Figure 7.

Since the sheet is confined by a feed slot 10 (Figure 6) or the feed rollers (other figures) as indicated by arrows 111 in Figure 7, the curvature of the channel is increased by this action thus improving, if anything, the beneficial straightening of bulges and wrinkles. If feed rollers, or other means, are provided to advance the sheet at a speed slightly greater than the plate speed the curvature gradually increases as the plate advances until the channel 109 may assume a form such as indicated by the dashed line by which more pressure is brought to bear against the plate.

It is preferred that the speed of the sheet advance be such as to keep the channel 109 close to the corona zone since bulges in the transfer sheet may have a tendency to re-form if a flat portion is allowed to develop between channel 109 and the start of the corona zone. However, the present arrangement greatly reduces the criticality in the rate of paper feed as the channel 109 can take up the slack. The problem of precise matching of the paper speed and plate speed is thereby reduced or eliminated.

In the claims, the reversal of parts is contemplated, and the parts which are movable and those which are stationary may be interchanged without exceeding the scope of the claims.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. An image transfer mechanism for electrostatically adhering images comprising a corona discharge electrode for attaching a transfer sheet and transferring a powder image, a plate feed mechanism for feeding an image plate under said electrode, and a sheet feed mechanism for feeding separate sheets of transfer material against an image plate in a sheet feed plane which makes a substantial angle at least greater than 5° with said plate and intersects said plate in a line substantially perpendicular to the direction of travel of said image plate and immediately in advance of said electrode, said sheet feed mechanism being spaced from the path of said image plate and including sheet guiding and advancing members, said sheet guiding and advancing members comprising a pair of parallel rollers which are in tangent contact in said sheet feed plane, and in which a common drive means is provided for said image plate feed mechanism and said parallel rollers to advance said image plate mechanism at a first linear speed and to advance said parallel rollers at a higher linear speed.

2. An image transfer mechanism for electrostatically adhering images comprising a corona discharge electrode for electrostatically attaching a transfer sheet and transferring a powder image, a plate feed mechanism for feeding an image plate under said electrode, and a sheet feed mechanism for feeding separate sheets of transfer material against an image plate in a sheet

11

feed plane which makes a substantial angle between 5 and 90° with said plate and intersects said plate in a line substantially perpendicular to the direction of travel of said image plate and immediately in advance of said electrode, said sheet feed mechanism being spaced from the path of said image plate and including sheet guiding and advancing members and drive means for said image plate feed mechanism and said sheet advancing member advancing said image plate mechanism at a first linear speed and advancing said sheet advancing member at a higher linear speed.
